UNITED STATES PATENT OFFICE.

BENJAMIN F. TEETOR, OF HAGERSTOWN, INDIANA.

LIFTING LEVER FOR CARS.

Application filed May 7, 1928. Serial No. 275,579.

The present invention relates to lifting levers for cars.

The present invention is particularly applicable to light inspection cars of the type adapted to run upon railroad rails. It is frequently necessary in inspection car service to lift said cars from the railroad rails and remount said car upon said rails. Inasmuch as inspection cars of modern type are relatively heavy, the job of lifting same, if the lifting action is a direct one, involves the exertion of considerable force by the operators. On the other hand, if levers are provided for the purpose, said levers are either obtrusive when not required for service, or require special holding means to prevent same from clattering if said levers are made removable.

An object of the present invention is to provide a light inspection car having lifting levers as permanent equipment thereon, which lifting levers may be readily swung into operative position or into unobtrusive position, said levers being free from rattle at all times.

A further object is to provide lifting levers for light inspection cars or the like, which levers are cheap to manufacture, easy to assemble and easy to operate.

A further object is to provide a light inspection car or the like having lifting levers as parts thereof, which lifting levers are sturdily supported upon rigid parts of the frame of said car.

Further objects will appear as the description proceeds.

Referring to the drawings—

Figure 1 is a perspective view illustrating a light inspection car having lifting levers applied thereto, which lifting levers embody the principles of the present invention;

Figure 2 is a top plan view of the frame of the light inspection car shown in Figure 1;

Figure 3 is a view in side elevation of one of the lifting levers shown in Figure 1, together with a portion of the light inspection car with which it cooperates;

Figure 4 is a top plan view of the structure shown in Figure 2, the non-obtrusive position of the lifting lever being indicated in dotted lines; and

Figure 5 is a bottom plan view of the construction shown in Figures 3 and 4.

The numeral 10 indicates the frame of an inspection car mounted upon the flanged wheels 11—11. Said flanged wheels are

adapted to ride upon railroad rails (not shown). The body 10 of the light inspection car preferably includes relatively strong beams 12—12, one of which extends across said body at the front thereof and another of which extends across said body at the rear thereof. The beams at the front and rear of the body 10 may be connected by a plurality of fore-and-aft members 13—13.

The numerals 14—14 indicate brackets secured to the cross beams 12 and to certain of the fore-and-aft members 13. As clearly shown in Figure 3, each bracket 14 has two legs, indicated by the numerals 15 and 16, disposed in substantially right-angular relationship with each other, the leg 15 having a substantially flat face adapted to bear against the outer face of the corresponding beam 12, the leg 16 having a flat face adapted to bear against the under side of the adjacent fore-and-aft member 13. In the illustrated embodiment of the present invention the leg 16 is offset, as indicated by the numeral 17, to accommodate the beam 12, which extends to a lower level than does the adjacent fore-and-aft member 13. A pair of rods 18 are provided, each having nuts 19—19 at the two ends thereof for securing brackets 14—14 to the corresponding beams 12—12 at the two ends of the car. The legs 16—16 are secured to the corresponding fore-and-aft members 13 by means of bolts 20.

Projecting from the leg 15 are a pair of arms 21—21, spaced apart a sufficient distance to provide clearance for the corresponding nut 19. Said arms 21—21 are provided with aligned apertures for the reception of a cylindrical member 22, which may be a tube. The upper extremity of the tube 22 is provided with the elbow 23, which has secured thereto the rod 24. Located on the outside of the tube 22 between the elbow 23 and the upper side of the arm 21 is the coil spring 25, which normally urges the tube 22 upwardly. Secured to the tube 22 near the lower extremity thereof is the pin 26 having its ends projecting beyond the outlines of the tube 22. The projecting ends of the pins 26—26, which ends are diametrically disposed relative to said tube 22, are adapted to be seated within the grooves 27—27 on the under side of the lower arm 21. It will be understood that the spring 25 will yieldably hold the projecting ends of the pin 26 within said grooves 27—27. Said grooves are arranged in quadrants, and the pin 26 is

so disposed relative to the length of the rod 24 that the spring 25 yieldably holds the corresponding rod 24 selectively either in a position disposed longitudinally of the inspection car or transversely of said inspection car in non-obtrusive position. The tube 22, elbow 23 and rod 24, it will be noted, constitute a lever capable of reacting against the arms 21-21 of the corresponding bracket 14.

A pair of brackets 14 may be located at either end of the car, and the positions of said brackets transversely of the car will be chosen to correspond with the center of mass of said car, whereby when a lifting movement is applied to the rods 24-24 at either end of the car, the resulting leverage action will be applied at the desired region transversely of the car.

It will be clear that when it is desired to apply a lifting force to either end of the car, the rods 24 will be swung out of the positions in which they are shown in Figures 1 and 2 into positions longitudinally of the car. The force necessary to swing said rods from obtrusive to non-obtrusive position, or conversely, is the force sufficient to compress the spring 25 an amount necessary to free the projecting ends of the pin 26 from the grooves 27-27. When the rods 24-24 have been swung to their operative positions, the projecting ends of said pins 26-26 will snap into the corresponding grooves 27-27 and said rods 24-24 will be releasably held in operative position. When it is desired to move the rods 24-24 back into unobtrusive position, a swinging movement will be communicated thereto sufficient to compress the springs 25-25 a sufficient amount to permit the freeing of the pin 26 from the grooves 27-27. The force of the spring 25 will be sufficient to hold the rods 24 against clattering, whereby the rods 24-24 will not only be in unobtrusive position, but will be noiseless as well.

Though a preferred embodiment of the present invention has been described in detail, it will be understood that many modifications will occur to those skilled in the art. It is intended to cover all such modifications that fall within the scope of the appended claims.

What is claimed is—

1. An inspection car including a frame having cross beams and fore-and-aft members, brackets secured to said cross beams and having portions secured to said fore-

and-aft members, a lever swingingly carried by each of said brackets, and spring-pressed detent means cooperating with each of said levers for holding said levers selectively in predetermined positions relative to said cross beams.

2. In a light inspection car, in combination, cross beams, a fore-and-aft member connecting said cross beams, a bracket engaging and secured to one of said cross beams and to said fore-and-aft member, a lever rotatably carried by said bracket, and spring-pressed detent means for releasably holding said lever in a plurality of selectable positions relative to said cross beam.

3. A car comprising, in combination, a cross beam, a bracket secured to said cross beam, a lever comprising a substantially vertical arm and a substantially horizontal arm, said vertical arm being provided with a spring, and a detent for selectively holding said vertical arm in a plurality of alternative positions relative to said bracket.

4. A car including a cross member, bracket means connected to said cross member symmetrically with respect to the center of mass of said car transversely of said car, lever means carried by said bracket means, and spring means reacting against said lever means for holding said lever means releasably in position lengthwise of said car or in a position transversely of said car.

5. A car including a cross member at an end thereof, fore-and-aft members abutting said cross member, a pair of brackets connected to said cross member and to said fore-and-aft members, said pair of brackets being disposed symmetrically with respect to the center of mass of said car transversely of said car, and spring means reacting against said levers for holding same releasably in selectable positions relative to said cross member.

6. In combination, a bracket for cooperation with an inspection car or the like comprising an L-shaped attaching portion and a bearing portion, an L-shaped lever having one leg thereof rotatably mounted within said bearing portion, a detent carried by said leg adapted to seat itself selectively within a plurality of angularly disposed recesses in said bearing portion and a spring for releasably holding said detent within one or another of said recesses.

Signed at Hagerstown, Ind., this 3rd day of May, 1928.

BENJAMIN F. TEETOR.
